(57) **CLAIM**

The ornamental design for a control module as shown and described.

DESCRIPTION

FIG. 1 is a first top front perspective view of a first embodiment of a control module;

FIG. 2 is a second top front perspective view thereof;

FIG. 3 is a first side elevational view thereof;

FIG. 4 is a second side elevational view thereof;

FIG. 5 is a front elevational view thereof;

FIG. 6 is a rear elevational view thereof;

FIG. 7 is a top plan view thereof;

FIG. 8 is a bottom view thereof;

FIG. 9 is a first top front perspective view of a second embodiment of the control module;

FIG. 10 is a second top front perspective view thereof;

FIG. 11 is a first side elevational view thereof;

FIG. 12 is a second side elevational view thereof;

FIG. 13 is a front elevational view thereof;

FIG. 14 is a rear elevational view thereof;

FIG. 15 is a top plan view thereof; and,

FIG. 16 is a bottom view thereof.

The broken lines in FIGS. 6 and 14 illustrate portions of the control module that form no part of the claimed design.

1 Claim, 14 Drawing Sheets
